1 Claim

ABSTRACT OF THE DISCLOSURE

An arrangement has been provided for relays to compensate for the effects of capacitive reactance of variable magnitude in lines connecting a control switch to the relay. A choke coil capable of storing more energy than can the coil of the relay is provided in parallel to the relay to maintain a sharp cut-off characteristic for the relay. A rectifier is series-connected between the relay and the central switch to maintain the flow of current in one direction only and thereby reduce pulse distortions.

The invention relates to circuits including a relay operated by a control switch and particularly to means for compensating for capacitive impedances of different magnitude in parallel with lines connecting the control switch to the relay.

Prior art systems to which this invention applies include a checking facility, equipped with a relay, for measuring pulses from a remote pulse contact via loaded lines of a telecommunication system. Thereby in the course of the line different transmissions or different lines can be alternately switched into the system causing capacitive impedances of different magnitudes to be placed in parallel to the pulse contact. Such capacitive impedances, being in parallel to the pulse contact and having various different magnitudes, cause the release or dropping periods of the relay of the checking facility to vary in length so that proper checking of the pulse contact is impossible.

In another relay arrangement known to the art the control contact is bridged for spark-quenching through an R/C-element. But here the R/C-element is firmly associated with the control contact and with the relay. Dimensioning of the R/C-element thereby depends on the magnitude of the relay impedance, so that a defined delay in the release of the relay can be assumed and thereby measures can be taken to balance the pulse distortions with the aid of succeeding facilities.

It is moreover, known that by a choke coil, shunted to the relay, in which the stored magnetic energy is higher than the one for the relay, said relay can be dropped quicker as would be the case when it is switched off.

A primary object of the invention is to provide a circuit arrangement for relays in which the pulse distortions of the relay, caused by differently large capacitive impedances parallel to the control switch, are essentially reduced. This is achieved according to the invention by applying the aforementioned measure that a choke coil is inserted in parallel to such a relay, the stored magnetic energy being higher than the one selected for the relay.

According to a further embodiment of the invention, the stored magnetic energy is essentially larger for the choke coil, for example, three times as large as the one

2

selected for the relay, in order to reduce the influence of the capacitive component of the impedance, parallel to the control switch, on the release delay of the relay.

When the controlled relay is an unpoled one, the negative current produced in such a relay by the choke coil 5 may cause under certain circumstances a re-energizing of such a relay for a short time. Therefore, and in compliance with a further embodiment of the invention, a poled rectifier is series-connected with the relay in the direction of the control current.

10 The invention is now in detail explained with the aid of an example.

FIG. 1 shows a circuit arrangement to test, for example a control switch x (which may be an electronic switch) 15 via a telecommunication line, having a capacitive impedance Z . The test equipment includes a relay A with which the pulses of the control switch x (in this case a relay contact) shall be determined. Series-connected with the relay A is a rectifier G and in parallel to said series-connection a choke-coil D is provided.

The arrangement will be considered at first without the rectifier G and the impedance Z.

The stored magnetic energy $\frac{1}{2}L_D J_D^2$ of the choke coil D is selected to be higher than the stored magnetic energy $\frac{1}{2}L_A J_A^2$ of the relay, so that the switch-off current i of the relay becomes negative, as shown in FIG. 2.

L_A and J_A represent the inductivity and the operating current of the relay A and L_D , J_D represent the inductivity and the operating current of the choke coil D. In FIG. 2, the relay current very steeply drops from the starting value i_1 to the negative value i_2 and thereupon slowly returns to the value zero. When an impedance Z of varying magnitude is in parallel with the line from the contact x the switch-off curve according to FIG. 3 is not as steep as the curve shown in FIG. 2, but compared with an arrangement without choke coil D it is much steeper, so that the influence of the impedances Z on the pulse distortion of the relay A is essentially reduced.

For further improvement of the arrangement the stored magnetic energy $\frac{1}{2}L_D J_D^2$ is made even higher, for example three times higher than the stored magnetic energy $\frac{1}{2}L_A J_A^2$, so that the switch-off curve, shown in FIG. 3 will be nearly as steep as the one shown in FIG. 1.

For relay A either a poled or a non-poled relay can be used. A non-poled relay can be energized again under certain circumstances at the aforementioned dimensioning, at least for a short time. Therefore, the rectifier G is provided to block the relay current in the negative direction. Thereby the switch-off curve according to FIG. 4 is obtained, the steepness of which is largely independent of the magnitude of the capacitive component of the impedance Z , so that the pulse distortion of the relay A remains extremely small, even due to the impedance Z .

While the principles of the invention have been described above in connection with specific apparatus and applications, it is to be understood that this description is made only by way of example and not as a limitation on the scope of the invention.

60 What is claimed is:

1. A circuit arrangement for a relay coupled to a central switch through means exhibiting different amounts of capacitive reactance, said circuit comprising:

65 a control switch,
 a relay,

means having capacitive reactance connecting said control switch to said relay,
a choke coil connected in parallel to said relay, said choke coil having the capability of storing greater amounts of magnetic energy than can the relay, and a rectifier inserted in series between said switch and said relay, said rectifier being poled in a direction permitting control current to flow only from the switch to the relay.
